UNITED STATES PATENT OFFICE.

SYLVESTER WOINA, OF LOST CREEK, WEST VIRGINIA.

DESIGN FOR A REST FOR CLOTHES AND OTHER ARTICLES IN WASHBOILERS.

50,858.

Specification for Design.

Patented May 29, 1917.

Application filed November 10, 1916. Serial No. 130,677. Term of patent 7 years.

To all whom it may concern:

Be it known that I, SYLVESTER WOINA, a citizen of Russia, residing at Lost Creek, in the county of Harrison and State of West Virginia, have invented a new, original, and ornamental Design for a Rest for Clothes and other Articles in Washboilers, of which the following is a specification, reference being had to the accompanying drawing, forming part thereof.

In the drawing:

Figures 1 and 2 are obverse and reverse views of the design, respectively.

I claim:

The ornamental design for a rest for clothes and other articles in wash boilers, as shown.

SYLVESTER WOINA.

Witnesses:

ALBERT V. KLACKO,
BLANCHE BAKER.
